CLAIM

We claim the ornamental design for an in-line dongle, as shown and described.

DESCRIPTION

FIG. 1 is a perspective view of the in-line dongle. FIG. 2 is a front plan view of the in-line dongle of FIG. 1. FIG. 3 is a back plan view of the in-line dongle of FIG. 1. FIG. 4 is a first side view of the in-line dongle of FIG. 1, the second side being a mirror image of that shown. FIG. 5 is a first end view of a connector receptacle of the in-line dongle of FIG. 1. FIG. 6 is a second end view of a connector receptacle of the in-line dongle of FIG. 1. FIG. 7 is a perspective view taken from the first end of the in-line dongle of FIG. 1, the connectors and cables between which the in-line dongle is inserted being shown in broken lines for environmental purposes. FIG. 8 is a perspective view taken from the second end of the inline dongle of FIG. 1, the connectors and cables between which the in-line dongle is inserted being shown in broken lines for environmental purposes; and, FIG. 9 is a perspective view of the in-line dongle of FIG. 1 within a vending machine.

The broken line depictions such as those of the connectors, cables, vending machine, and portions of the in-line dongle are included for environmental purposes and form no part of the claimed design.

The gaps shown in phantom are meant to indicate that the in-line dongle may be of any length and/or width as indicated.
